Attorney*

UNITED STATES PATENT OFFICE

JOHN H. DRAPER, OF CANTON, MASSACHUSETTS

WASHING MACHINE

Application filed July 10, 1930. Serial No. 466,903.

This invention relates to machines for washing articles such as clothing and household fabrics, and has particular reference to mechanism for continuously and alternately immersing and squeezing the articles.

One of the objects of my invention is to provide a machine having an endless series of pockets for the articles, said series being flexible throughout and mounted to travel between squeezing rolls and through a bath of cleansing fluid.

Another object is to provide such a machine in which the collections of articles will pass between the squeeze rolls in overlapping succession, whereby excessive parting and closing of the rolls will be avoided.

With the above objects in view, and others such as will be referred to, the invention consists in the construction and combination of parts such as hereinafter described and claimed.

Of the accompanying drawings in which I have illustrated one embodiment of my invention:

25 Figure 1 is a vertical elevation of the machine.

Figure 2 represents a transverse view of the same.

30 Figure 3 represents a section on line 3—3 of Figure 2.

Figure 4 is a perspective view of a portion of the pocketed belt.

Similar reference characters designate similar parts or features in all of the views.

35 A suitable tub or tank is illustrated at 10, said tub having brackets 11 for the shafts of squeeze rolls 12, 13, said shafts having gears 14. The parts or members of the machine so far referred to may be of any well-known or preferred structure, and the rolls may be 40 driven by any preferred power.

45 My invention relates to the means whereby the articles to be washed are subjected to repeated immersions in cleansing liquid in the tub or tank, alternating with squeezing operations by the rolls. Said means consists of a flexible endless belt having pockets for holding collections of goods to be cleaned. Such a carrier, broadly, is not new.

50 In carrying out my invention I utilize rope

netting material such as that employed for fish nets or seines. To construct the carrier or belt I fold a wide strip of netting 15 at its mid-width 16 (Fig. 4) and secure the selvages 17 together, preferably, but not necessarily by cord knots 18. Such strip of doubled netting may be of any length desired, according to the capacity wanted for the machine. The two ends of the folded strip are connected by suitable means such as by tying together the pieces of loose rope or cord at the ends of the folded strip, thus making the net carrier endless. In practice, this endless carrier of netting is usually longer in proportion to the size of the pockets presently described, than illustrated in Figures 1 and 2.

If the pockets were to be provided in straight rows across the belt, the operation hereinafter described would be interfered with by the differences in thickness of the loaded pocket portions of the belt when passing between the squeeze rolls. Therefore, an important feature of my invention resides in providing the belt with pockets having a staggered relationship to each other, so that although the belt as a whole has a plurality of longitudinal rows of pockets, no two pockets will arrive simultaneously at the bite of the squeeze rolls.

80 In some structures included within the scope of my invention, the pockets may be made of material separate from the belt and attached thereto in staggered relationship. In the embodiment of the invention illustrated, however, said pockets are provided in a simple and effective manner by cord-tying together the two layers of the belt netting along somewhat U-shaped lines indicated at 19, in the proper locations other than directly side by side, such as illustrated, and slitting the outermost layer of the netting on lines meeting the upper ends of the U-shaped tied lines, such slits then providing openings 20 through which articles can be inserted into the pockets between the two layers of the belt netting. As illustrated by Figures 2 and 4, the described tying at 19 and slitting at 20 is effected in such locations that the resulting pockets across the carrier belt are in

staggered relationship. The described method of providing the pockets, by such tying at 19 and slitting at 20, constitutes another important feature of my invention, whether the relative positioning of the pockets is staggered or not.

While it is convenient to make the belt of a wide strip of netting and folding it at its mid-width, I do not limit myself thereto, as 10 it may consist of two strips of netting or similar flexible material, with the edge portions of the strips suitably connected.

I have illustrated the carrier belt as depending from the lower one of a single pair 15 of squeeze rolls. The said carrier may, however, be differently hung. For instance, two or more pairs of squeeze rolls may be employed, and the carrier belt may travel in the form of a plurality of loops instead of the 20 single one illustrated.

When some or all of the pockets have been filled with goods to be laundered, the openings 20 are closed by cordage knots 21 or any other preferred closing devices, and then the 25 machine is operated in the well-known way to cause the pocketed articles to be repeatedly immersed in cleansing liquid in the tub and be subjected to squeezing action by the rolls, for as long a time as may be desirable.

30 It is not always necessary to close the openings at the tops of the pockets. For instance, when the articles to be cleansed are in bags of netting, such bags are not likely to slip out of the carrier pockets, especially if 35 the loaded bags closely fit the carrier pockets. And while I consider it best to so arrange the pockets that the openings needed to enable the articles to be inserted therein and removed therefrom shall be at the tops of 40 the pockets on the rising portion of the belt, I do not limit myself thereto, as for some purposes, or for some classes of goods, it may be preferred to provide vertical entrances to the pockets so that articles may be inserted 45 or removed in a side-wise direction.

Having now described my invention, I claim:—

1. A washing machine comprising a receptacle for fluid, squeeze-rolls above said receptacle, and an endless flexible belt passing 50 between said rolls, said belt having transverse rows of pockets in side by side staggered relationship.

2. A washing machine comprising a receptacle for fluid, squeeze-rolls above said receptacle, and an endless belt of double thick porous material passing between said rolls, the two thicknesses being connected together in a plurality of locations to form pockets, and 60 the outer thickness having slits to give access to such pockets.

3. A washing machine comprising a receptacle for fluid, squeeze-rolls above said receptacle, and an endless belt consisting of a strip 65 of porous material passing between said rolls,

said strip being folded at its mid-width to provide inner and outer layers, the two layers being connected together in locations to form pockets in side by side staggered relationship and the outer layer having slits to 70 give access to such pockets.

In testimony whereof I have affixed my signature.

JOHN H. DRAPER.
